UNITED STATES PATENT OFFICE

LOUIS HUFFMAN, OF TORONTO, ONTARIO, CANADA, ASSIGNOR TO TORONTO TYPE
FOUNDRY COMPANY, LIMITED, OF TORONTO, CANADA

MANIFOLDING SALES BOOK

Application filed November 2, 1931. Serial No. 572,518.

This invention relates to manifolding sales books in which triplicate copies of records are required and is of the type wherein separate carbon sheets are provided for each set or unit of leaves throughout the book.

One of the objects of this invention is to provide a simple practical sales book of the above character in which the carbonized side 10 of the transfer sheet will not be exposed to and soil the hands of the sales person using same, or merchandise with which it may happen to come in contact.

Another object of this invention is to provide a book wherein the record sheet which remains in the book will not be in contact with the carbonized side of a transfer sheet.

Still another object is to provide a convenient method of removing from the book 20 one or a plurality of used carbon sheets at one time.

Other objects will in part be obvious and in part be referred to hereinafter.

I attain my various objects by constructing 25 a sales book having bound therein alternately a strip or set of three connected record sheets adapted to be folded in zig-zag fashion, and a strip or set of two connected transfer sheets adapted to be folded at their point of connection. The first record sheet, which is bound into the book and eventually bears the third or triplicate record, is of thin translucent paper, while the other two sheets may be of ordinary opaque writing paper. The transfer sheets are carbonized on one side, and when the book is prepared for use the second sheet is folded in between the original record sheet and the duplicate record sheet so that its carbonized face is adjacent the upper side of the duplicate record sheet and the carbonized face of the first transfer sheet is adjacent the under side of the transparent triplicate record sheet. The record sheets are perforated along their lines of fold so that 45 they may be separated, and the carbon sheets are perforated adjacent the binding of the book. To enable the carbon sheets to be easily removed after use without removing the triplicate sheet the carbon sheets extend beyond the end of the triplicate sheet sufficient-

ly far to enable them to be grasped at their line of fold and torn off along the perforation adjacent the binding of the book.

My invention is hereinafter more particularly described and illustrated in the accompanying drawing, in which

Fig. 1 is a perspective view showing the book in operative position, the original and duplicate sheets of the first set of records having been removed and the triplicate sheet 60 and carbon sheet thrown back over the front cover;

Fig. 2 a perspective view of a set or unit of record sheets folded as shown in Fig. 1;

Fig. 3 a perspective view of a set or unit 65 of transfer sheets folded as shown in Fig. 1, and partly torn and folded back to show the reverse side of the sheets;

Fig. 4 a perspective view, partly broken away, of a modified arrangement of the 70 sheets in which the second carbon sheet is adhered to the back of the original record sheet;

Fig. 5 a perspective view, partly broken away, of another modified arrangement of 75 the sheets in which the second carbon sheet is adhered to the face of the duplicate sheet; and

Fig. 6 a perspective view, partly broken away, of another modified arrangement of 80 sheets in which the first carbon sheet is adhered to the triplicate sheet.

In the drawing like numerals of reference indicate corresponding parts in the different figures.

The strip or set of record sheets comprises the original record sheet 1, the duplicate record sheet 2 and the triplicate record sheet 3. The original sheet 1 and the duplicate sheet 2 may be made of opaque paper while 90 the triplicate sheet 3 is either of thin translucent paper adhesively secured to the duplicate sheet or else may be a part integral with the duplicate sheet and treated by known methods to render it translucent. Each triplicate sheet 3 is provided with a binding margin or stub 3^a at one end thereof. By 95 its other margin 3^b the triplicate sheet, if a separate piece, is glued or otherwise secured to the duplicate sheet 2. The back of the 100

duplicate sheet 2 is connected to the face of the triplicate sheet 3 in such a manner that it lies over the triplicate sheet as illustrated in the drawing. At the margin or end of the duplicate sheet opposite to the margin to which the triplicate sheet is secured, the original sheet 1 is connected. The sheet 1 is preferably integral with the sheet 2 and is provided with perforations at the point of connection therewith. The record sheets 1 and 2 are preferably of ordinary opaque paper, but for some purposes these may be of the same thin transparent paper as the sheet 3 and formed integral therewith. When in use the sheet 1 is folded over the sheet 2 so that the record sheets are thus in zig-zag form and constitute a set of triplicate record leaves.

The carbon sheets 4 and 5 are preferably integral and provided with a line of fold at their point of connection. The carbon sheet 5 is provided with a binding margin 5^a, and the sheets are carbonized on their upper face so that when the sheet 4 is folded over the sheet 5 the carbonized faces are opposite one another on the inside. A line of perforation is formed across the carbon sheet 5 at the point of connection between the binding margin 5^a and the carbon sheet proper.

A plurality of sets or strips of record sheets and transfer sheets are bound into a cover by means of metal stitches 18, the record sheets alternating with the carbon sheets. The cover comprises a front 7, a back 8 and an insert 9. The cover is of cardboard or other stiff material, and the insert 9 is designed to be inserted between the sheets upon which the record is being made and the remainder of the sheets so that the record will not be impressed upon the latter.

The record sheets and carbon sheets are arranged in the book in the following manner. The record sheets are folded in zig-zag form as already described and the carbon sheet 4 is folded between the original sheet 1 and the duplicate sheet 2.

The operation and manner of using a book of this character is as follows: Assuming the book to be opened as shown in Fig. 1, the first set of record sheets having been used, the original and duplicate sheets detached from the book, the triplicate sheet along with the carbon sheet thrown back over the front cover and the second set of record and transfer sheets lying over the insert or separating sheet 9, the second set of sheets or leaves is in position for recording a transaction. The record of the transaction is made on the original sheet 1 and is reproduced on the duplicate sheet 2 through the medium of the carbon sheet 4, and on the back of the translucent record sheet 3 through the medium of the carbon sheet 5, which lies beneath the same with its carbonized side facing upward in contact with the record sheet 3. The copy

recorded on the back of the translucent triplicate sheet is legible on its face. By the process above described an original and two copies of the record have been made.

After completing the record as above described, the original and duplicate sheets are detached from the book in the following manner: The clerk places the first finger of his left hand on the projecting carbon sheets at their adjoining marginal edges 10 where they project beyond the record sheets. He then grips the upper left hand corner of the original and duplicate sheets 1 and 2, at their point of connection, between the thumb and first finger of the right hand and pulls the sheets in a direction away from himself as far as they will go over the front cover. The carbon sheet 4 does not extend right up to the point of connection between the record sheets 1 and 2, and there is therefore a space left so that the sheets 1 and 2 may be grasped and pulled out without pulling the carbon sheet with them. In case the carbon sheet 4 might be caught by the fingers, the pressure is just sufficient to pull away the record sheets 1 and 2 without pulling the transfer sheet 4, which is, of course, held in position by the first finger of the left hand during this operation. When the operation just described has been completed the original, duplicate and triplicate record sheets are lying over the back of the book. Next, the first finger of the left hand is removed from its position on the carbon sheet to the upper left hand corner of the triplicate sheet where a firm downward pressure is applied. Then with the right hand the original and duplicate sheets are detached from the triplicate sheet by pulling the same towards the right and away from the triplicate sheet. The

duplicates will ordinarily part from the triplicates at their point of connection, but if desired perforations 11 may be formed in the duplicate adjacent its point of connection with the triplicate. These perforations will facilitate the separation of the sheets. This will leave the triplicate sheet lying over the carbon sheet of the first set, and the carbon sheet of the second set from which the record sheets 1 and 2 have just been removed are left lying on the insert 9. The original and duplicate record sheets which have been removed are separated along the line of perforation at their point of connection and the original is given to the customer and the duplicate is kept for the record. The carbon sheets of set 2 are then thrown back over the cover.

The manifolding book must then be arranged for the recording of another transaction. To do this the upper right hand corner of the original and duplicate leaves with the carbon sheets arranged therein is grasped and pulled back over the back of the cover, whereby the third set of record and transfer

sheets is pulled out from beneath the insert 9. The fold of the original and duplicate record sheets extends beyond the upper edge of the insert 9 in order that it may be grasped as described. When the third set has been removed as described it is let fall back in position on the insert 9. The set is then ready for recording another transaction.

It will be noted that owing to the fact that the adjoining marginal edges 10 of the carbon sheets extend beyond the end of the triplicate record sheet the carbon sheets can be detached from the book by grasping the edges 10 and tearing along the perforations 6, without removing the triplicate sheet which remains in the book as a record.

In Fig. 4, I show the transfer sheet 4 pasted, glued or otherwise attached by its upper margin to the back of the original sheet 1 at the top thereof adjacent its point of connection with the duplicate sheet 2 while the sheet 5 is bound in the book as before. The carbon sheets 4 and 5 are provided with perforations 12 at their point of connection so that when the original record sheet 1 is removed the carbon sheet 4 remains attached thereto. If desired, the carbon sheet 4, which remains attached to the original sheet 1, can then be creased in the middle and folded back on itself so that the carbonized surfaces face each other and do not soil the hands or other objects when the record sheet 1 has been detached and handed to the customer. The advantage of attaching the carbon sheet 4 in the manner described is that additional entries or corrections can be made after the record sheet 1 has been detached and the changes or corrections will be reproduced on the duplicate sheet without having to make the correction again on the copy.

In Fig. 5, I show a construction in which the upper margin of the carbon sheet 4 is adhered to the face of the duplicate sheet 2 adjacent its point of connection with the original sheet 1, while the sheet 5 is bound in the book as before. In this case the carbon sheets are also provided with perforations 12 at their point of connection and when the record sheets are removed the carbon sheets 4 remain attached to the faces of the duplicate sheets, and can be used in making additional entries or corrections after the sheets have been separated.

In Fig. 6, I show the carbon sheet 5 affixed to the end of the triplicate record sheet 3 adjacent its point of connection with the duplicate sheet 2. In this case also the carbon sheets are provided with a line of perforation at their point of connection and the carbon sheet 4 is affixed to the original sheet 1 as in Fig. 4. In this case the carbon sheet 5 remains permanently in the book affixed to the triplicate record sheet 3.

It will be noted that a book constructed after the manner herein described is simple

and quick to operate and clean to handle since the carbonized sides of the carbon sheets are not exposed when the book is used or lying on the desk open or closed.

What I claim as my invention is:

1. In a sales book a manifolding unit comprising a record sheet of translucent paper provided with a stub for binding in the book; a record sheet connected at one end to the outer end of the said translucent sheet; an original record sheet connected to the other end of the said second record sheet, the three sheets normally lying in superimposed relationship; a carbon sheet having its upper face carbonized, positioned beneath the first mentioned record sheet; and a carbon sheet, positioned above the second mentioned record sheet, and having its under face carbonized.

2. A manifolding unit according to claim 1 in which the first mentioned carbon sheet is provided with a stub for binding in the book and the two carbon sheets are connected by their ends remote from the stub.

3. A manifolding unit according to claim 1 in which the first mentioned carbon sheet is provided with a stub for binding in the book and the two carbon sheets are connected by their ends remote from the stub and in which the upper end of the upper carbon sheet is adhesively secured to one of the upper two record sheets adjacent their line of connection.

4. A manifolding unit according to claim 1 in which the first mentioned carbon sheet is provided with a stub for binding in the book and the two carbon sheets are connected by their ends remote from the stub and in which the upper end of the upper carbon sheet is adhesively secured to the underside of the uppermost record sheet.

5. A manifolding unit according to claim 1 in which the first mentioned carbon sheet is provided with a stub for binding in the book and the two carbon sheets are connected by their ends remote from the stub and in which the upper end of the upper carbon sheet is adhesively secured to the upper side of the intermediate record sheet adjacent its line of connection with the uppermost record sheet.

6. A manifolding unit according to claim 1 in which the first mentioned carbon sheet is provided with a stub for binding in the book and the two carbon sheets are connected by their ends remote from the stub and in which the lower end of the under carbon sheet is adhesively secured to the lower end of the first mentioned record sheet.

7. A manifolding unit according to claim 1 in which the carbon sheets are connected by their ends remote from the stub.

8. A manifolding unit according to claim 1 in which the carbon sheets are connected by their ends remote from the stub and in which the upper end of the upper carbon sheet is

adhesively secured to one of the upper two record sheets adjacent their line of connection.

9. A manifolding unit according to claim 1 in which the carbon sheets are connected by their ends remote from the stub and in which the upper end of the upper carbon sheet is adhesively secured to the underside of the uppermost record sheet.

10. A manifolding unit according to claim 1 in which the carbon sheets are connected by their ends remote from the stub and in which the upper end of the upper carbon sheet is adhesively secured to the upper side of the intermediate record sheet adjacent its line of connection with the uppermost record sheet.

11. A manifolding unit according to claim 1 in which the carbon sheets are connected by their ends remote from the stub and in which the lower end of the under carbon sheet is adhesively secured to the lower end of the first mentioned record sheet.

12. A manifolding unit according to claim 1 in which the connected ends of the upper two record sheets extend nearer to the stub end of the unit than the end of the underlying carbon sheet whereby the said ends may be grasped without also gripping the said end of the carbon sheet.

13. A manifolding unit according to claim 1 in which the ends of the two carbon sheets are connected and extend further from the stub end of the unit than the adjacent end of the record sheets whereby the said ends of the carbon sheets may be grasped without also gripping the said ends of the record sheets.

14. A manifolding unit according to claim 1 in which the connected ends of the upper two record sheets extend nearer to the stub end of the unit than the end of the underlying carbon sheet whereby the said ends may be grasped without also gripping the said end of the carbon sheet and in which the ends of the two carbon sheets are connected and extend further from the stub end of the unit than the adjacent end of the record sheets whereby the said ends of the carbon sheets may be grasped without also gripping the said ends of the record sheets.

15. A manifolding book comprising a plurality of sets of record leaves each comprising a record sheet of translucent paper provided with a stub bound in the book, a record sheet adhesively secured at one end to the outer end of the said translucent sheet, an original record sheet connected to the other end of the said second record sheet, the three sheets normally lying in superimposed relationship; and carbon sheets connected to the book so that when a record is being made, a carbon sheet may be face upward beneath the translucent sheet and another carbon sheet may lie face downwards over the intermediate record leaf.

16. In a sales book a manifolding unit comprising a record sheet of translucent paper provided with a stub for binding in the book; a record sheet adhesively secured at one end to the outer end of the said translucent sheet; an original record sheet connected to the other end of the said second record sheet, the three sheets normally lying in superimposed relationship; a carbon sheet having its upper face carbonized, positioned beneath the first mentioned record sheet; and a carbon sheet, positioned above the second mentioned record sheet, and having its under face carbonized.

17. A manifolding unit according to claim 16 in which the connected ends of the upper two record sheets extend nearer to the stub end of the unit than the end of the underlying carbon sheet whereby the said connected ends may be grasped without also gripping the said end of the carbon sheet.

18. A manifolding unit according to claim 16 in which the connected ends of the two carbon sheets extend further from the stub end of the unit than the adjacent end of the record sheets whereby the said connected ends of the carbon sheets may be grasped without also gripping the said ends of the record sheets.

19. A manifolding unit according to claim 16 in which the connected ends of the upper two record sheets extend nearer to the stub end of the unit than the end of the underlying carbon sheet whereby the said connected ends may be grasped without also gripping the said end of the carbon sheet and in which the connected ends of the two carbon sheets extend further from the stub end of the unit than the adjacent end of the record sheets whereby the said ends of the carbon sheets may be grasped without also gripping the said ends of the record sheets.

20. A sales book comprising a cover; a plurality of triplicate manifolding units each complete in itself secured to the cover, each unit comprising three connected record sheets arranged in superposed relationship and connected at one end of one of the sheets to one end of the cover, the lowermost record sheet being translucent, and two connected transfer sheets arranged in superposed relationship and connected at one end of one of the sheets to the same end of the cover.

Signed at Toronto, Canada, this 23rd day of September, 1981.

LOUIS HUFFMAN.
